United States Patent Office

Des. 178,727
Patented Sept. 11, 1956

178,727

CAN OPENING MACHINE

William E. Gundelfinger, House Springs, Mo., assignor
to The Dazey Corporation, St. Louis, Mo., a corpora-
tion of Missouri

Application January 9, 1956, Serial No. 39,678

Term of patent 14 years

(Cl. D22—2)

FIG. 1.

FIG. 2.

FIG. 3.

FIG. 4.

FIG. 5.

Fig. 1 is a top plan view of a can opening machine, showing my new design;

Fig. 2 is a side elevational view of the can opening machine shown in Fig. 1;

Fig. 3 is an end elevational view thereof;

Fig. 4 is an elevational view of the end opposite to that shown in Fig. 3, and

Fig. 5 is an elevational view of the side opposite to that shown in Fig. 2.

I claim:

The ornamental design for a can opening machine as shown.
